TRANSPARENCY VIEWER

James H. Parcher, Conshohocken, Pa., assignor to Sylvania Electric Products, Inc., New York, N. Y., a corporation of Massachusetts

Application April 24, 1957, Serial No. 45,870

Term of patent 14 years

(Cl. D61—1)

Fig. 1

Fig. 2

Figure 1 is a front elevational view of a transparency viewer, showing my new design;

Figure 2 is a rear elevational view;

Figure 3 is a side elevational view, the opposite side having substantially the same appearance; and

Figure 4 is a top plan view thereof.

A portion of the drawing figures is diagonally lined to indicate transparency.

I claim:

The ornamental design for a transparency viewer, substantially as shown and described.
